[57] CLAIM

The ornamental design for a filter cartridge, as shown and described.

DESCRIPTION

FIG. 1 is a front perspective view of the filter cartridge showing our new design;
FIG. 2 is a rear perspective view thereof;
FIG. 3 is a right side elevational view thereof, the left, top and bottom side views being identical thereto;
FIG. 4 is a front end elevational view thereof;
FIG. 5 is a rear end elevational view thereof; and,
FIG. 6 is a perspective view of the filter cartridge in full lines with the broken lines showing environmental association matter being for illustrative purposes only and forming no part of the claimed design.
